HAT CONSTRUCTION

Peter J. Xeros, Dallas, Tex.

Application March 12, 1951, Serial No. 215,086

1 Claim. (Cl. 2—181)

1

This invention relates to a hat construction.

In the manufacture of hats, a sweat band conventionally formed of leather is secured inside the crown of the hat and various means have been devised for securing the sweat band within the crown. Certain types embody the use of stitching but such securing means results in the transfer of moisture and oils by capillary attraction to the crown and the latter becomes stained. Certain other types embody the use of adhesive in place of stitching for securing the sweat band to the crown, but in such types the reed is encased in waterproof fabric, and the bead formed by the reed in the fabric projects slightly below the leather sweat band, and when the hat is pulled tight on the head the reed binds unduly, particularly about the forehead.

It is, therefore, an object of this invention to provide a sweat band and method and means for attaching the band to the hat so that moisture and oils will not pass through the band to the crown.

Another object of this invention is to provide a sweat band wherein the reed is encased within the leather band instead of the fabric attaching band, and a moistureproof fabric band is adhesively secured between the leather band and the inside of the crown.

In a modified form of this invention the reed is stitched into the reverted lower edge of the leather band, and the fabric band is vulcanized or otherwise adhesively secured to the leather band over the stitches.

With the above and other objects in view, my invention consists in the arrangement, combination and details of construction disclosed in the drawings and specification, and then more particularly pointed out in the appended claim.

In the drawings:

Figure 1 is a fragmentary inner detailed elevation of a hat band constructed according to an embodiment of this invention.

Figure 2 is a fragmentary outer side elevation partly broken away and in section of a sweat band.

Figure 3 is a fragmentary plan view of the fabric band securing member.

Figure 4 is a fragmentary sectional view on an enlarged scale taken on the line 4—4 of Figure 1.

Figure 5 is a fragmentary sectional view of a modified form of this invention.

Referring to the drawing the numeral 10 designates generally the crown of a hat and the numeral 11 designates the brim. The hat 10—11

2

may be formed out of felt, straw or other material. A sweat band generally designated as 12 is disposed interiorly of the crown 10 and comprises a leather band member 14 which is reduced in thickness at its lower portion by skiving one side of the band member 14 so that the lower edge of the band member 14 may be readily reverted or bent upwardly as indicated by the upward bent portion 15.

10 A reed 16 is disposed interiorly of the bend 15 and the reed 16 with the bend 15 are secured together and to the outer side of the body of the band member 14 by means of an adhesive 17. Preferably the adhesive 17 is of the thermosetting type being moistureproof so that the adhesive will not be affected by moisture from the head. The band member 14 is adapted to be secured interiorly of the crown 10 by means of a reverted fabric band 18. The band 18 comprises an inner wall 19 which is secured by means of an adhesive 20 to the lower portion of the band 14 and to the reverted portion 15 of band 14. The fabric band member 18 also includes an outer wall 21 which is secured by means of an adhesive 22 to the inner side of the crown 10. The right or lower edge of the fabric band 18 is disposed at a point above the reed 16, and the reverted lower edge of the leather band 14 so that the reed 16 with the lower edge of the band 14 will be disposed in downwardly projecting relation below the attaching member 18, and the latter will normally hold the leather band 14 at its lower edge out of contact with the juncture between the crown 10 and the brim 11.

25 35 The adhesive 20 and 22 is also a thermosetting or waterproof adhesive which will not be affected by moisture or oils from the head. The fabric band member 18 is of the conventional type which is preferably glazed or coated on one side thereof with a waterproof coating, and this glazed surface of the attaching band 18 is preferably disposed between the walls 19 and 21.

40 45 In attaching the sweat band 12 within the crown 10 the attaching band 18 may be initially secured by the adhesive 20 to the outer side of the band member 14 which at this time is reverted at its lower edge with the reed 16 disposed in the loop formed by the reversion of the band member 14. After the band member 18 has been secured to the band 14 the wall 21 may be secured to the inner side of the crown 10.

50 55 It will, of course, be understood that the attachment of the attaching band 18 to the band 14 and the crown 10 may be performed in a single operation which will simultaneously attach band

18 to band 14 and to the crown 10. This band structure and the method of applying the same to the hat will provide a sweat band structure which will prevent the passage of moisture or oils from the sweat band to the crown of the hat and thereby discolor the crown.

Referring to Figure 5 there is disclosed a modified form of this invention wherein the reed 16^a is secured in the folded lower edge 15^a of the leather band 14^a by means of stitching 23. The 10 reverted or U-shaped fabric attaching 18^a is vulcanized or adhesively secured to the outer side of the leather band 14^a and covers the stitches 23 so that moisture or oils saturating the stitches 23 will be held against flowing outwardly.

What is claimed is:

In a hat construction, a sweat band and means securing the band within the crown of the hat, said sweat band comprising a leather band tapering from an intermediate portion thereof to form 20 a relatively sharp edge, and being folded to form a reverted portion, the sharp edge of which is juxtaposed to a line on the band at the start of the taper, a reed in the bight formed by the reverted portion, thermoplastic adhesive means se- 25

curing said reed in position and securing the reverted portion to the body of the band, an intermediate band of U-shape in cross section and terminating above said fold line, adhesive means 5 securing said intermediate band to said reverted portion, and adhesive means securing said intermediate band to the inner side of the crown of the hat.
